(57) **CLAIM**

The ornamental design for a phone holder, as shown and described.

DESCRIPTION

FIG. 1 is a perspective view of a phone holder showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of another state of the phone holder thereof;

FIG. 9 is a perspective view of another state of the phone holder thereof; and,

FIG. 10 is an enlarged view of the selected portion 10 in FIG. 3.

The broken lines shown in the drawings depict portions of the phone holder that form no part of the claimed design.
